UNITED STATES PATENT OFFICE.

HARRY C. ADAM, OF ST. LOUIS, MISSOURI.

DESIGN FOR A BOWL FOR LIGHTING-FIXTURES.

48,806.

Specification for Design.

Patented Apr. 4, 1916.

Application filed January 24, 1916. Serial No. 74,049. Term of patent 14 years.

To all whom it may concern:

Be it known that I, HARRY C. ADAM, a citizen of the United States, residing at St. Louis, Missouri, have invented a certain new, original, and ornamental Design for a Bowl for Lighting-Fixtures, of which the following is a specification, reference being had to the accompanying drawing, forming part thereof.

Figure 1 of the drawings is a side ele-

vational view of my new design for a bowl for lighting fixtures; and Fig. 2 is a bottom plan view thereof.

I claim:

The design for a bowl for lighting fixtures, as shown.

HARRY C. ADAM.
